UNITED STATES PATENT OFFICE.

BRADFORD B. HOLMES, OF THE UNITED STATES ARMY, ASSIGNOR TO NEWTON D. BAKER, SECRETARY OF WAR, UNITED STATES OF AMERICA, TRUSTEE.

RECOIL MECHANISM FOR GUNS.

1,396,114.

Specification of Letters Patent. Patented Nov. 8, 1921.

Application filed November 22, 1919. Serial No. 339,994.

(FILED UNDER THE ACT OF MARCH 3, 1883, 22 STAT. L., 625.)

To all whom it may concern:

Be it known that I, BRADFORD B. HOLMES, major, United States Army, a citizen of the United States, stationed at Washington, 5 District of Columbia, have invented an Improvement in Recoil Mechanism for Guns, of which the following is a specification.

The invention described herein may be used by the Government, or any of its officers or employees in prosecution of work for 10 the Government, or by any other person in the United States, without payment to me of any royalty thereon.

This invention relates to improvements in 15 recoil mechanism for guns with special reference to recoil mechanism employing a recuperator system of the hydropneumatic type.

The object of the invention is to provide 20 a piston construction in the recuperator cylinder for separating the gas and liquid in a simple and inexpensive manner, by eliminating the necessity for the costly mounting and packing construction heretofore used.

25 Another object of the invention is to provide a structure which may be disassembled, to a large extent, in the field without permitting the escape of gas or of all of the liquid, and without the usual precautions, 30 since the mechanism itself is provided with safety means.

Another object of the invention is to provide 35 gas containing means with a safety valve which will be opened to permit the escape of gas under pressure upon undue leakage of the liquid of the recuperator system.

Another object of the invention is to provide 40 a "telltale" or signal, in combination with a piston of the recuperator cylinder for indicating when the supply of liquid should be replenished.

Further objects of the invention and novel combinations of parts will appear as the description progresses.

45 Figure 1 is a perspective view of a gun and recoil mechanism of my invention in position on the gun carriage;

Fig. 2 is an end view partly in section of the gun and recoil mechanism removed from 50 the carriage;

Fig. 3 is a vertical section on the line B—B of Fig. 2;

Fig. 4 is a horizontal section on the line A—A of Fig. 2;

Fig. 5 is a vertical section on the line 55 C—C, Fig. 3; and

Fig. 6 is a vertical section on the line D—D of Figs. 3 and 4.

The cradle 1 is mounted on the top carriage of the trail by means of trunnions 2. 60 The cradle embodies the body of the recoil mechanism 3, in which is formed a recoil cylinder 4 and a recuperator cylinder 5. The gun 6 is mounted for longitudinal movement in the guide-rails 7 of the cradle.

Within the recoil cylinder 4 is the usual recoil piston 8 and piston rod 9, the said cylinder being closed at one end by the screw-plug 10 and the other end by suitable packing 11 and screw-plug 12.

70 The gun 6 is secured to the piston-rod 9 by means of a recoil lug in the usual manner so that on recoil of the gun, the piston-rod and piston move therewith.

The recuperator cylinder 5 is connected 75 with the recoil cylinder 4 by means of a passageway 13, which is controlled by a spring-pressed valve 19 urged to its seat by a spring 20. Extending from proximity of the stem of the valve 19 is a valve follower 21, which 80 projects into a casing 22 secured to the recuperator body. Belleville washers 26 are held in compression between a head 24 mounted on the valve follower and a collar 25 formed on the valve follower which abuts 85 against a nut 25' for limiting the movement of the valve follower in one direction. The head 24 is retained on the valve follower by means of the nut 24'. The nut 25' retains the valve cage 19' in position. The head 24 is movable longitudinally on the follower for the purpose of placing additional compression on the Belleville washers as will hereinafter be described.

A variable recoil slide 27 is formed with 95 a tapered or wedge shaped cam portion 28 which is adapted to act on head 24 for increasing or decreasing the tension on Belleville washers 26 by forcing the head 24 to slide on the valve follower. The slide 27 en- 100

gages with a cam (not shown) on the trunnions 2 and as the gun moves in elevation or depression, the slide and cam 28 are correspondingly moved and act upon the head 24 so as to adjust the tension on the Belleville washers 26 and thus through the valve follower tend to hold the recoil valve 29 to its seat with a force depending for magnitude upon the position of the gun so that 10 most of the energy of recoil is absorbed by the oil pushing valve 19 off its seat against heavy spring pressure.

After passing the valve 19, the oil enters the space 30 in the recuperator cylinder between 15 a piston-head 31 and the rear end 32 of the recuperator cylinder. This end of the recuperator cylinder is formed with a projecting annular lip 33 for a purpose which will hereinafter appear. Within the recuperator cylinder, rearward of the piston-head 31 is a flexible metallic envelop 34 having convolutions forming in effect a bellows. The rear end of the bellows is closed by a piston-head, 36 having a central sleeve 25 37 closed at its forward end and extending into the bellows for the reception of a sleeve 38 projecting from piston-head 31 which slides in said sleeve 37 in a telescopic manner. This sleeve is provided with a longitudinal groove 39 for engaging a pin 40 projecting from piston head 36, which restricts the sleeve from rotation with respect to said piston-head.

Inclosed in the telescoping sleeves and 35 compressed between the two piston-heads of the recuperator cylinder is a spiral spring 41 secured at one end to the sleeve 37 of the piston-head 36 and at the other end to the piston-head 31 by any suitable means such 40 as a nut 42, as shown in Fig. 4.

The piston head 31 is formed on its rearward surface with a groove 43 in which is inserted the annular packing 44. This annular packing is adapted to cooperate with the 45 projecting lip 33, as will hereinafter appear.

The forward end of the recuperator cylinder is closed by means of an air-cap 45 held in place against a shoulder 46 formed in the interior of the recuperator cylinder by a retaining nut 47. The cap 45 has an inwardly 50 extending flange 48 to which is secured by means of screw threads, the rearward end of the bellows 34. The cap 45 is centrally bored and in this opening is placed an air valve 50 in the form of a check valve of ordinary construction, which is also sealed against leakage by means of packing 52 held in place by means of cap 53 which screws into the cylinder closure 45. It is 55 evident that the gas supply of the recuperator bellows may be replenished through the valve 50.

The piston head 36 is formed with an aperture which is controlled by means of a 60 valve 56 normally held to its seat by means

of a spring compressed between the rearward face of the piston-head and a flange 57 formed on the end of the valve stem. This valve comprises a safety feature which is considered of the utmost importance. 70

The rearward end of the recuperator cylinder is closed by means of a plug 60 held in place by suitable packing, and the retaining nut 61. This plug is apertured so as to align with passage 13 and contains the recoil valve 19 which has been previously described. This plug also contains the radially extending counter-recoil passage 62 which is controlled by the check valve 63. The counter-recoil passage 62 radiates from the 80 central opening 64, the forward end of which is partially closed by the apertured plug 65 through which extends the tapered counter recoil buffer 66. The recoil buffer is secured to the piston-head 31 by means 85 of the screw-threads 67 formed on the annular flange of the base of the counter recoil buffer engaging corresponding threads on a central annular flange 68 of the piston head 31 forming in effect a housing for the spring 90 retaining nut 42. Also extending from the central aperture 64 is a radial drain passage 70 normally closed by means of the plug 72.

It will be understood that on counter-recoil, the check valve 63 will be raised from 95 its seat so that the oil may find its way through passage 62 and connecting passage 13 to the recoil cylinder.

Near the end of the counter-recoil the recoil buffer 66 enters the central orifice 100 of the screw plug 65 thereby cutting down the flow of oil and allowing the gun to go gradually to battery position. Also extending through the plug 60 is bored a small passage 77 which is counter bored for a portion of its length indicated at 79 to a larger diameter. 105

A rod 78 is mounted for sliding movement in the passage 77 and has an integral flange 80 for sliding movement in the portion of 110 larger diameter. The rod 78 is normally urged forward by means of a spring 81 which is compressed between the flange 80 and an aperture retaining nut 82 and packing 83. 115

The rod 78 is extended beyond the flange 80 and passes through the spring 81 and the packing 83 and retaining nut 82. This rod also extends inward so as to contact with the piston-head 31 and is adapted to act as a 120 "telltale" or signal.

An oil reservoir 85 is formed in the recuperator body by means of the bent plates 86, which are secured to the recuperator body in any manner which will form a fluid 125 tight joint. This reservoir communicates with the inlet valve 88 of an oil pump 89 by means of annular passage 90 and passage 91 through the recuperator body. The piston of the oil pump is indicated at 92 and 130

is adapted for reciprocatory movement in the cylinder formed in the bushing 93.

The piston 92 is reciprocated by means of the handle 95 which operates on the pinion 94 mounted on the shaft 95'. The pinion 94 meshes with a rack 96 formed on the piston extension. On the working stroke of the oil pump piston 92 the oil is forced through a longitudinal groove passage 98 controlled by an outlet valve 99 into the space 30 of the recuperator cylinder and the oscillation of the handle 95 is continued until the "telltale" indicates a sufficient supply of oil which in this case is when the rod 77 is flush with the end of the recuperator cylinder.

The recuperator cylinder is formed with longitudinal grooves 102 in the vicinity of the normal position of the piston head 36 so as to permit oil to pass from one side to the other of said piston head.

The operation of the device is as follows:

On the recoil of the gun, the oil in the rear of the recoil piston is forced through passage 13 and valve 19 to the space 30 of the recuperator cylinder, the resistance of the passage to the oil depending upon the elevation of the gun in positioning the cam slide and head 24 of the valve follower.

The oil entering the space 30 forces back the piston-heads 31 and 36 thereby compressing bellows 34 and the gas contained therein. As the bellows are compressed the oil contained in the convolutions is squeezed out and passes by means of grooves 102 into the space between the two pistons so that the piston head 36 will travel forward a little faster than the piston head 31. The spring 41, however, will tend to restore the two piston-heads to the same relative position.

The counter-recoil is effected by the expansion of air within the bellows forcing the oil back to the recoil cylinder through the orifice in plug 65, passages 64 and 62 and check valve 63 as previously described.

In case of leakage of oil, by the blowing out of a packing or by long idleness, or other cause, the packing ring 44 in piston head 31 is brought into contact with lip 33 by the pressure (about 1,200 pounds per square inch) of the air or other gas within the bellows behind it, thus forming a tight joint.

The oil in space 30 and around the bellows is therefore, trapped and cannot escape. It is only necessary, therefore, to repair the packing and pump in some more oil by means of oil pump 89. This feature enables the recoil rod, piston, oil pump, counter recoil system, recoil valve and the plug 60 to be disassembled in the field for repairs without permitting the escape of gas.

In case oil within the space between the two pistons should leak out, the safety valve

56 coming in contact with piston head 31 will be forced open and the gas within the bellows will be permitted to escape thus preventing the bellows from being blown up.

This invention provides a recoil mechanism of simple construction which can be continued in use for a long period of time away from any source of supplies, since the gas of the bellows will require slight replenishing and the oil may be replenished from the reservoir 85 without further equipment.

The invention is also valuable because of the fact that practically all of the parts of the gun which are likely to become out of order may be disassembled and repaired in the field without danger of injury either to the person making the repairs or to the mechanism.

Having thus described my invention, what I claim as new and desire to secure by Letters Patent, is:—

1. In a recoil mechanism for guns, a recuperator mechanism of the hydropneumatic type comprising spaced piston-heads, a spring compressed between said piston heads and a valve extending through one of said piston-heads and adapted to be operated by contact with the other of said piston heads.

2. In a recoil mechanism of the class described, a recuperator cylinder, a closure for the same containing a recoil valve, a counter-recoil valve, an oil pump cylinder and piston, and a rod extending through said closure for indicating the amount of oil contained in the recuperator cylinder.

3. In a recoil mechanism of the class described, a recuperator cylinder formed at one end with a projecting annular lip, a piston-head within said cylinder, an annular packing ring on said cylinder adapted to engage said lip upon the escape of oil from the recuperator cylinder thereby forming a seal for the prevention of further leakage.

4. In a recoil mechanism of the class described, a recuperator cylinder, a plurality of piston-heads slidably mounted therein, a bellows containing a fluid under pressure, an annular packing ring on the face of one of said piston-heads, and an annular lip on the cylinder for engaging said packing ring for preventing leakage of liquid contained between said piston-heads and around said bellows.

5. In a recoil mechanism of the class described, a recoil cylinder and piston therefor, a recuperator cylinder containing a liquid and a gas under pressure, means for separating the liquid from the gas, a removable plug for closing one end of said recuperator cylinder, a recoil passage connecting said cylinders and extending through said plug, and a counter-recoil channel extending through said plug and communicating with said passage-way.

6. In a recoil system, a recoil cylinder and piston therefor, a recuperator cylinder containing a liquid and a gas under pressure, a passage-way connecting said cylinders, means for separating the liquid from the gas, a removable plug for closing one end of said recuperator cylinder and a safety device for releasing the gas pressure upon excessive longitudinal movement of said means.
- 10 7. In a recoil mechanism for guns, a recuperator mechanism of a hydropneumatic type, comprising an expandible container for fluid under pressure and an automatic safety means for relieving the fluid pressure.
- 15 8. In a recoil mechanism for guns, a re-
- cuperator cylinder, an expandible container for fluid under pressure located within the cylinder and automatic means for relieving pressure in the container.
9. In a recoil mechanism, a recuperator cylinder, a piston in said cylinder, a removable plug for closing one end of said cylinder, a rod having an intermediate collar extending through said plug, a spring engaging said collar for yieldingly urging said rod into contact with said piston, said rod adapted to project beyond the plug to indicate the fluid contents of the cylinder.

BRADFORD B. HOLMES.
